HORN SUPPORT FOR CAN BODYMAKER

William P. Winters, Cincinnati, Ohio, assignor to American Can Company, New York, N.Y., a corporation of New Jersey

Application July 30, 1954, Serial No. 446,813

6 Claims. (Cl. 113—12)

The present invention relates to machines for making can or container bodies having side seams which require bumping on a horn or mandrel and has particular reference to an improved support for firmly holding the horn or mandrel during the seam bumping operation.

An object of the instant invention is the provision in a can bodymaker of an improved horn support designed to eliminate heavy moving parts and reduce the stroke of eccentric and reciprocating movements to increase the efficiency of the machine while reducing construction and maintenance costs.

Numerous other objects and advantages of the invention will be apparent as it is better understood from the following description, which, taken in connection with the accompanying drawings, discloses a preferred embodiment thereof.

Referring to the drawings:

Figure 1 is a front view of a can bodymaker embodying the instant invention, with parts broken away and parts shown in section;

Fig. 2 is a sectional view of the bumping station of a can bodymaker, the view being taken substantially along the line 2—2 in Fig. 1, with parts broken away;

Fig. 3 is a transverse sectional view of the bumping station as taken substantially along the broken line 3—3 in Fig. 1, with parts broken away;

Fig. 4 is a sectional view taken substantially along the line 4—4 in Fig. 3, with parts broken away;

Fig. 5 is a fragmentary sectional view similar to Fig. 2 and showing the upper portion of the bumping station with the moving parts in a different position; and

Fig. 6 is an enlarged sectional view as taken substantially along the broken line 6—6 in Fig. 4, with parts broken away.

As a preferred or exemplary embodiment of the instant invention the drawings illustrate principal parts of the side seam bumping station of a sheet metal can bodymaker of the character disclosed in United States Patent 1,625,091, issued April 19, 1927, to John F. Peters on Can Body Making Machine.

In such a can body making machine or bodymaker, flat sheet metal blanks are formed into cylindrical can body shape on a longitudinally disposed horn or mandrel 11 (Figs. 1, 2, 3, 4 and 6) and are advanced along the horn in a step-by-step manner through several working stations where the partially formed bodies are formed with hooked edges and the edges aligned and interengaged and at a bumping station A are bumped or squeezed together tightly to produce a tubular cylindrical can body B having an interfolded and locked side seam C ready for soldering. This is a conventional can body making procedure.

The horn 11 for a major portion of its length is fixedly supported at its bottom in a horizontal position in a frame 12 which constitutes the main frame of the bodymaker. At the bumping station A, however, the horn 11 is not fixedly supported but overhangs a vertically reciprocable hammer 14 which is vertically and longitudinally aligned with the interengaged hook edges of a partially formed can

2

body at rest on the horn 11. The hammer 14 is supported in a vertical slide 15 which operates in slideways 16 secured in the machine frame 12. The slide 16 is reciprocated vertically toward and away from the horn 11 in time with the advancement of the partially formed can bodies along the horn, by a crank 17 mounted on a crank-shaft 18 journaled in bearings 19 formed in the machine frame 12. The crank shaft 18 is actuated in any suitable manner as by a pulley 21 carried on one end of the shaft.

Since the hammer 14, in bumping or compressing the hook edges of a can body to form the side seam C, produces considerable strain on the overhanging portion of the horn 11, the horn at this station is supported or backed up from above, i. e. opposite the hammer 14, to absorb the bumping impact. This support is yieldably held against the horn 11 to permit advancement of a bumped can body out of the bumping station and to allow for the entrance of a succeeding body for a bumping operation. For this purpose a longitudinally disposed horn support member or clamp shoe 23 is located at the bumping station A adjacent the top of the horn 11 where it is directly opposite the bumping hammer 14 and where it engages against a can body B at the bumping station. In some machines the clamp member 23 may be used alone without the hammer 14 to clamp and hold the can body in place on the horn at a station other than the bumping station.

The horn support member 23 is formed with a vertically disposed, preferably rectangular shaped stem or shank 24 (Figs. 4 and 6) which is slideably disposed in a vertical slideway 25 formed in a bracket 26 secured to a web section 27 of the frame 12. The support member 23 is maintained normally under light pressure exerted by a pair of light springs 29 (Fig. 6) interposed between the top of the member and the bottom of the bracket 26 to yieldably hold the member against the horn 11. A screw 31 extending transversely through the bracket 26 and through a clearance slot 32 in the shank 24 holds the shank in place in the bracket.

With the support member 23 lightly pressed against the horn 11, can bodies B may be readily pushed into place between the horn support member and the horn 11 at the bumping station for the seam bumping operation.

During the bumping operation, the support member 23 is pressed hard against the body interposed between it and the horn to fully support or back up the horn against the impact of the bumping hammer 14. This additional supporting pressure is brought about by a rocker cam 35 (Fig. 6) which is disposed above the support member shank 24 and which is formed with a depending edge cam segment 36 having an eccentric convex cam face 37. The cam face 37 engages against a similar eccentric concave cam face 38 formed in the top end of the support member shank 24.

The rocker cam 35 is oscillated in time with the operation of the hammer 14 to slide its eccentric cam face 37 into engagement with the eccentric cam face 38 of the shank 24 to bear hard against the shank and thus exert an endwise pressure thereagainst to force the support member 23 down tightly against the horn 11, as shown in full lines in Fig. 6, to back up the horn during impact of the hammer. After the bumping impact, the rocker cam 35 is oscillated in an opposite direction to swing the eccentric cam face 37 away from the eccentric cam face 38, as shown in dot and dash lines in Fig. 6, to relieve the endwise pressure on the shank 24 and the support member 23 to return the member to its yieldable condition as outlined above.

Oscillation of the rocker cam 35 is effected through a rocker shaft 41 upon which the rocker cam is mounted for partial rotation therewith. The rocker shaft 41 is carried in a pair of spaced bearings 42 formed in the

bracket 26. The shaft 41 is rocked through a pressure exerting stroke (counterclockwise as viewed in Fig. 6) and then through a return or pressure relieving stroke (clockwise as viewed in Fig. 6) by a pair of oppositely disposed integral rocker arms 44 carried on one end of the rocker shaft 41. The rocker arms 44 carry cam rollers 45, 46 (Figs. 2, 3, 4 and 5) which operate simultaneously and continuously against a segmental edge cam 48 formed on one end of a lever 49. The opposite end of the lever 49 is mounted on a pivot pin 51 secured in a boss 52 which extends out from one of the shaft bearings 42.

The lever 49 is rocked on its pivot pin 51 through an upright eccentric rod 54, the upper end of which is adjustably secured by adjusting nuts 55 (Fig. 4) in a pivot block 56 pivotally carried in the outer end of a lever extension 57 of the lever 49. The lower end of the eccentric rod 54 is attached to an eccentric ring 58 of an eccentric 59 (Figs. 1 and 2) mounted on and rotating with the crank shaft 18 to provide timed relation of the operation of the horn support member 23 with the operation of the hammer 14.

The cam face of the segment cam 48 upon which the cam rollers 45, 46 operate is formed with a pair of cam nodes or high spots 61, 62 and a pair of adjacently disposed intervening cam depressions or low spots 63, 64. These nodes and depressions are spaced so that when one of the cam rollers 45, 46 is on a node, the other is in a depression and vice versa, as best shown in Fig. 5.

When the hammer 14 moves upwardly toward the horn 11 for a bumping operation, the eccentric 59 draws down on the eccentric rod 54 and thus rocks the lever 49 in a counterclockwise direction as viewed in Fig. 5. This shifts the segment cam 48 in a counterclockwise direction and causes the upper cam roller 46 to ride up onto the upper node 62 of the cam and causes the lower roller 45 to enter the depression 63 of the cam. This shifting of the cam rollers 45, 46 rocks the rocker shaft 41 (Fig. 6) in a counterclockwise direction as mentioned above and hence causes the edge cam 36 to exert a downward endwise pressure on the shank 24 and horn support member 23 to back up the horn 11 during impact of the hammer 14 as hereinbefore explained.

In a like manner, the return or downward movement of the hammer 14 after completing a seam bumping operation, effects, through the eccentric 59, eccentric rod 54, and lever arm 49, a clockwise swinging of the segment cam 48. This causes the lower cam roller 45 to ride up on the lower cam node 61 and simultaneously causes the upper roller 46 to ride into the upper depression 64. The rocker shaft 41 is thus rocked, by the shifting of the cam rollers 45, 46 in a clockwise direction as viewed in Fig. 6 to rotate the edge cam 36 in this same direction and thereby relieve the backing-up pressure on the shank 24 and horn support member 23 as hereinbefore explained.

Hence through operation of the eccentric 59 in time with the movement of the hammer 14, the segment cam 48 fully controls the simultaneous action of the two cam rollers 45, 46 and thus controls the application of pressure to the horn support member 23 so that the horn is fully supported during the impact resulting from the can body side seams bumping operation and at the proper time relieves the pressure on the horn to permit passage of the can bodies into and out of the bumping station. With such a construction of the segment cam 48 and rocker rollers 45, 46 for actuating the horn support member 23, the stroke of the eccentric 59 and the strain on the other operating parts can be reduced to a minimum to greatly increase the efficiency and decrease the maintenance costs of the entire unit.

In order to provide for proper timing or setting of the segment cam 48 through adjustment of the lever 49 relative to the eccentric rod 54, a visible indicator is included in the device. This indicator comprises a pointer 71 (Figs. 1, 2, 3 and 5) which is secured to the

lever 49 adjacent its pivot pin 51 and which swings with the lever adjacent a stationary indicator dial 72 fixed to the adjacent boss 52. The dial carries visible indexing characters 73 of any desired order to indicate the position of the segment cam 36 which is hidden in the bracket 26 and thereby facilitates proper setting of the cam.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a high speed can body making machine having a can body supporting horn and a horn support member mounted adjacent said horn for movement toward said horn, the improvement which comprises the combination of a rotary cam mounted adjacent said horn support member and engageable thereagainst for pressing said member toward said horn, a pair of rocker arms operatively connected with said rotary cam and disposed radially in divergent directions from the axis of said cam, an actuating cam mounted for rotary oscillating movement adjacent said rocker arms and having a cam face in constant engagement with both of said rocker arms for oscillating said arms in unison, and means for oscillating said actuating cam to thereby impart a rotary oscillating movement to said rotary cam to move said rotary cam gently into and out of pressing engagement against said horn support member.
2. The mechanism of claim 1 wherein said cam face of said actuating cam is formed with a pair of spaced nodes and at least one intervening depression.
3. The mechanism of claim 1 wherein each of said rocker arms is provided with a cam roller disposed in engagement with said cam face of said actuating cam.
4. In a high speed can body making machine having a can body supporting horn and a horn support member mounted adjacent said horn for movement toward said horn, the improvement which comprises the combination of an oscillatable edge cam mounted adjacent said horn support member for rotary movement and having a curved cam face engageable against said horn support member for exerting an endwise pressure thereagainst to force said member toward said horn, a shaft for mounting said oscillatable edge cam, a pair of rocker arms mounted on said shaft and extending radially therefrom in divergent directions, an actuating cam mounted for rotary oscillating movement adjacent said rocker arms and having a cam face which is in constant engagement with both of said rocker arms for oscillating said rocker arms in unison, and means for oscillating said actuating cam to thereby oscillate said shaft and rotate said curved oscillatable edge cam face gently into and out of pressing engagement with said horn support member.

5. The mechanism of claim 4 in which said rotatable edge cam is provided with an eccentric convex cam face which is engageable against an eccentric concave cam face formed in said horn support member to exert an endwise pressure thereagainst to force said horn support member toward said horn.

6. In a high speed can body making machine having a can body supporting horn, the combination of an elongated clamp member extending along said horn for clamping engagement thereagainst at a working station, said clamp member having a shank slideably mounted adjacent said horn, said shank terminating at its outer end in an eccentric actuating face, an oscillatable edge cam having an eccentric face disposed adjacent and engageable with the actuating face of said shank for exerting an endwise pressure against said shank to clamp said clamp member against said horn, a pair of rocker arms connected with said edge cam and disposed radially in divergent

directions from the axis of said edge cam, a lever pivotally mounted at one end and having a free end disposed adjacent said rocker arms, an actuating cam on the free end of said lever and having a cam face in constant engagement with both of said rocker arms for rocking said arms, and means for oscillating said actuating cam to rock said arms and thereby move said clamp member toward said horn to clamp a can body therebetween.
